UNITED STATES PATENT OFFICE.

ERWIN F. BAHLMANN, OF MILWAUKEE, WISCONSIN.

TARGET-THROWING APPARATUS.

Application filed January 19, 1922. Serial No. 530,377.

To all whom it may concern:

Be it known that I, ERWIN F. BAHLMANN, a citizen of the United States, and resident of Milwaukee, in the county of Milwaukee and State of Wisconsin, have invented new and useful Improvements in Target-Throwing Apparatus, of which the following is a description, reference being had to the accompanying drawings, which are a part of this specification.

This invention relates to certain new and useful improvements in target traps and refers more particularly to an apparatus of this character so designed and constructed as to be capable of use in a gallery or field.

One objection to the present type of target traps is that they require the constant service of an attendant and, therefore, it is an object of this invention to so design an apparatus of the character described whereby the necessity of a trap attendant is entirely eliminated.

Another object of this invention is to provide an apparatus of the character described having means permitting its remote control, either as an automatically varying trajectory throwing machine, or a single trajectory throwing machine, at the will of the operator.

It is another object of this invention to provide an apparatus of the character described which is capable of throwing either a single target, a pair of targets at an operation, or more than two if desired.

Another object of this invention is to provide an apparatus of the character described which will throw a cycle of trajectories and which will repeat any particular trajectory if desired.

This invention has for a further object to provide an apparatus of the character described which will produce trajectories at short range which simulate the paths of clay birds as viewed by the shooter, thus establishing short range or indoor trap shooting.

A still further object of this invention is to provide an apparatus of the character described designed for delivering flying targets at trajectories suitable for small arms practice for all types of arms.

And a still further object of this invention

is to provide an apparatus of the character described having means adjustable to throw targets in any inclined plane as well as in a substantially vertical plane to thus produce a trap capable of general trap shooting.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side elevation of a target throwing trap using my improved target directing device;

Figure 2 is an edge view of the flexible target directing device detached from the trap;

Figure 3 is a plan view thereof;

Figure 4 is an enlarged detailed view of the outer end of the trajectory varying connecting rod;

Figure 5 is an enlarged top view thereof;

Figure 6 is a section through the trajectory varying crank on plane of line 6-6, Figure 1 showing adjustment features;

Figure 7 is an end view of trap illustrated in Figure 1, the plates being sectioned on a vertical plane through axis of the support;

Figure 8 is a view of trajectory varying shaft and operating parts which permit remote control;

Figure 9 is a view of the main crank for operating trap;

Figure 10 is a detailed view of casting for supporting operating end of trajectory varying mechanism;

Figure 11 is a detailed view partly in section and partly in diagrammatic elevation, of the device used to place either or both

of the magazines into operation from a remote point, said section being taken on the line 11—11 of Figure 15;

Figure 12 is a sectional view taken on the line 12—12 of Figure 1;

Figure 13 is a front view of the device used to separate double trajectories any desired degree;

Figure 14 is an edge view thereof;

Figure 15 is a fragmentary detailed view illustrating the arrangement of mechanism used to adapt machine to throwing doubles;

Figure 16 is a detailed view of the throwing arm employed to throw doubles;

Figure 17 is a side elevation of a trap equipped with a modified form of device for varying the direction of a target thrown from the trap;

Figure 18 is a fragmentary sectional view taken on the line 18—18 of Figure 17;

Figure 19 is a fragmentary sectional view taken on the line 19—19 of Figure 17;

Figure 20 is a fragmentary sectional view taken on the line 20—20 of Figure 17;

Figure 21 is a detailed view of the throwing arm, said view being taken on the line 21—21 of Figure 22, and

Figure 22 is a fragmentary view, partly in section and partly in elevation taken on the line 22—22 of Figure 17.

Referring now more particularly to the accompanying drawings in which like numerals designate like parts throughout the several views, the numeral 5' designates a suitable support provided with bearings 6' and 7' for shafts 8' and 9', respectively. Shaft 8' is hollow with a throwing shaft 10' journaled therein, on one end of which is mounted a throwing arm 11' and on the other end of which is secured a collar 12' carrying a spring finger 13' adapted to engage behind a stop 14' carried by one yoke member of a universal joint 15' made fast to shaft 8'. Stop 14' is made cam shape so that shaft 10' cannot be driven in retrograde direction. Pinion 35 is attached to shaft 8' as shown.

Shaft 8' is adapted to be rotated by a rod or other control member 16' connected with the universal joint 15' and has its outer end journaled in bearing member 17' located at some point remote from the apparatus, preferably at the position occupied by a shooter, the outer end of the rod having a hand crank 18' secured thereto for convenient operation. Rotation of shaft 8' will bring pin 14' into engagement with finger 13', consequently rotating shaft 10' and when shaft 10' is rotated, the energy stored in a spring 19' is increased to the point at which the throw takes place. Spring 19' is connected at one end to a crank which carries the throwing arm and at its other end to an adjustable eye-bolt 20' attached to a bracket 20" secured in place by a cap screw 21'

which serves to secure the plates 22' and 22" and a race member 23, in spaced relation, forming a target guide.

Member 23 has its outer major portion formed by a strip of resilient metal 24 secured at its inner end, as at 25, at the termination of member 23. Member 24 is normally urged to the position illustrated in dotted lines in Figure 1, against the spacing washers carried by securing bolts 26, strip 24 having laterally projecting lugs 27 on one longitudinal edge which are movable in involute slots or openings 28 in one plate 22', the inner terminations of said slots being arranged on an imaginary arc struck from the axis of shaft 10'.

Passing through the uppermost slot 28 and engaging the outer face of member 24, is a pin 29 provided with a guiding groove 29' formed on the outer end of a rod 30 having its inner end pivotally secured to a crank arm 31, fixed to one end of shaft 9'. Slidably, but non-rotatably mounted on the other end of shaft 9' is a yoke member of a universal joint 33 attached to a gear wheel 34, gear wheel 34 being movable to mesh with a pinion 35 fixed to shaft 8', set collar 32 preventing longitudinal movement of shaft 9' when the gear is shifted. Connected with the universal joint member 33 is a control rod or shaft 36, the outer end of which is slidably, as well as rotatably, journaled in a bearing member 37 mounted at a point adjacent bearing 17', means being provided for the securement of shaft 36 in either of its two positions, meshing gears 34 and 35, or with said gears disengaged.

Rotatably mounted in bearing 37 is a bushing 38 in which rod 36 is rotatably and slidably mounted, said bushing being provided with a crank or handle 39 and having a spring urged pin or plunger 40 adapted for engagement in either of the grooves 41 or 42 formed in rod 36, and when plunger 40 is engaged in groove 42, a pin 43 carried by shaft 36 engages in a notch 44 in the inner end of bushing 38 to drivingly connect said bushing and shaft whereby rotation of crank 39 will revolve shaft 9' independently of shaft 8'. When the parts are in the position illustrated in Figure 8, bushing 38 is free of shaft 36 and consequently rotation of crank 39 will have no effect, but a rotation of crank 18' will simultaneously rotate shafts 8' and 9' through the medium of gears 34 and 35. When it is desired to lock shaft 36 in any desired position of adjustment, bearing 37 is drawn tight by use of the binding bolt 45.

The normal friction of bearing 37 on bushing 38 is adjusted so that shaft 36 will retain any desired setting in spite of the effect of the spring member 24 and the cranks attached to shafts 36 and 9', when gears 34 and 35 are disengaged. Bushing 38 is held

against longitudinal displacement in bearing 37 by the set screw 37' which extends into a groove turned in bushing 38.

In order that a fresh target 46 may be 5 positioned at the inner end of the target guide in the path of arm 11' for each actuation, a feed trough 47 communicates therewith, said trough being preferably so designed and constructed as to supply the tar- 10 gets either in singles or pairs. In the event trough 47 be empty when a target is placed therein at its receiving end and in order to prevent the jumping of the target into the guideway when it reaches its adjustable 15 limit stop 48, to be later described, I provide one or more dogs 49, as best illustrated in Figures 1 and 15.

Stop 48 is in the form of a pin carried by an arm or lever 50 journaled to one plate 20 22' which pin projects through an arcuate slot 51 in said plate and being normally yieldably urged to the position illustrated in Figure 1 by a spring 52 coiled about an eye-bolt 53 carried by the adjacent guide 25 plate. Spring 52 is confined between a tension adjusting end 54 and a lug 55 on lever 50 through which bolt 53 slidably passes, the movement of pin 48 under action of spring 52 being limited to a position spaced 30 from the beginning of the guideway by a distance slightly less than the diameter of targets 46 by adjusting nuts 56. As will be readily obvious, when the energy of the throwing arm actuating means is released, 35 the pressure brought to bear against the target 46, which is in position to be operated upon, will cause stop 48 to yield and target 46 will be ejected.

As it is often times highly desirable that 40 a pair of targets be thrown at a single operation, I provide means whereby this feature is obtainable and at the same time a single target can be thrown by the manipulation of but one bar. Referring to Figures 45 11 and 15, a partition plate 57 is centrally located in trough 47 changing it so that the targets pass therethrough in pairs, as is obvious from the drawings, in which case two stops 48 are employed as well as two 50 dogs 49 and the outer end of the throwing arm 11' is forked as at 58 to accommodate partition 57. A double race or race of double width is used as 23—23 Figure 11.

As often times it is desirable to throw 55 but one target, I provide means for preventing the feeding to the guideway of the targets on either side of partition 57, which means consists of a slidably mounted bar 59 secured against rotation having two spaced spring fingers 60 which are adapted 60 to have their pointed or roughened laterally projecting ends 61 projected into the trough through openings 62 in the sides thereof.

65 In order that the targets of the pairs will

not be thrown at the same trajectories, the outer end portion of member 24 preferably has one longitudinal half provided with a spring plate 63 which has its inner end made fast to member 24 and its outer end 70 adjustable by a set screw 64, as best shown in Figures 13 and 14.

From the foregoing description taken in connection with the accompanying drawings it will be readily obvious that the operation of my machine is substantially as follows: Trough 47 is filled with targets from any suitable point of supply and the innermost target or targets will be positioned as illustrated in Figures 1 and 15 by dotted 75 lines. When the operator, if he desires to employ the automatically changing trajectory mechanism, moves pin 40 out of engagement with groove 42, and shifts shaft 36 inwardly until pin 40 engages in groove 80 41 when gears 34 and 35 will be in mesh. Crank 18' is then rotated in a clockwise direction to engage pin 14' behind finger 13' to thus drivingly connect shafts 8' and 10' and rotate the throwing member 11' in the 85 direction of the arrow in Figure 1 storing up energy in spring 19'.

By reason of gears 34 and 35 being meshed, crank 31 is rotated at a considerably slower speed than shaft 10' to vary the 90 position of race member 24 and as the arm 11' reaches the position illustrated by dotted lines at the right of Figure 1, the energy of spring 19' is released and the target or targets, engaging stop 48 is rapidly swept 95 through the guide and impelled therefrom, the trajectory being governed by the position of the outer end of member 24 at the time the target leaves the apparatus. Should it be desired to repeat the last 100 trajectory thrown, this can be done by turning crank 18' one revolution counter-clockwise then proceed again in clockwise direction. Three rotations counter-clockwise will cause 105 the repetition of the third last trajectory 110 etc. due to pin 14' being formed cam shape on its rear face.

The variation between extremes of trajectories thrown is governed by the position of the pivot 30' of pitman 30 with respect to the axis of shaft 9', the pivot 30' being adjustably secured to crank 31, as illustrated in Figure 6. In the event smaller targets are employed, I provide means for adjusting the dead point of the throwing member by slotting the opening in the securing plate 20'' through which the securing bolt 21' passes in order to provide lateral adjustment of member 20' to avoid subjecting the target to impact. Stop members 48 are adjustable by means of nuts 56 to accommodate different sizes of targets. 115

When it is desired to eliminate the automatic changing of the trap, rod 36 is moved outwardly and pin 40 engaged in groove 42. 120 125 130

Rotation of shaft 16' then delivers targets only. Trajectories are adjusted at the will of the operator by the manipulation of crank 39. The targets are presented to the 5 guide in pairs or singles by the mechanism illustrated in Figures 11 and 15 and the operation of this feature will be apparent from the above description, notches 59' serving to lock bar 59 against accidental 10 arrangement. Bar 59 and target supply trough 47 terminate preferably near cranks 18' and 39, thus centralizing the complete remote control of the apparatus.

In Figures 17 to 22, inclusive, I have illustrated a slightly modified form of my invention, in which, in lieu of the hollow shaft 8', a solid shaft 65 is provided for the throwing member 11^a which is preferably in the form of a spring rod secured to shaft 65 and having coils 66 with its outer end struck laterally and then longitudinally, as at 67, for engagement with an adjustable stop 68 when it reaches a position of engagement with the innermost target or targets 46. Adjustment 20 of stop 68 is provided to vary the amount of energy stored in the throwing spring when it becomes operative as well as to avoid impact for any size of target employed. When end 67 engages stop 68, the continued rotation of shaft 65 stores energy in the coil 66 until member 11^a is shortened sufficiently to disengage end 67 from stop 68. Member 11^a then sweeps through the target guide and 30 impels the target or targets engaged from 35 the apparatus.

In lieu of the flexing race member 24, in this form of my invention, I provide one or more shifting race members 69 the inner peripheries of which are struck on an arc employing the axis of shaft 65 as a center. Members 69 are connected together by suitable securing bolts 70 and 71, which have secured thereto the adjacent ends of a substantially T-shaped lever 72 having its inner 40 end journaled about bearing 6'. Bolt 71 is provided with suitable roller bearings 73 which engage a portion of the periphery of plates 22' and 22'' forming a track 74 and bolt 70 passes through an arcuate slot 75 in 45 one plate 22' whereby shifting or swinging of lever 72 on its pivot will vary the position of the outer ends of race member 69 with respect to the vertical and consequently adjust the trajectory of the machine.

50 The oscillation of lever 72 is provided by a slotted crank arm 76 formed on the inner end of lever 72 to which the crank 31 is adjustably secured, as at 77.

The operation of this form of my invention will be readily apparent from the foregoing description and, therefore, a detailed statement of the operation is deemed unnecessary. As will be readily apparent by examination of Figures 21 and 22, a weight 78 55 is adjustably secured to throwing member

11^a in order that the inertia thereof may be readily adjusted as will be obvious.

One of the movable race sections 69 is provided with arcuate slots at 70 and 71 respectively. Both slots are struck on an arc using 70 the axis of shaft 65 as a center. Thus by loosening bolts 70 and 71, this section can be shifted so that double trajectories may be separated any desired degree.

What I claim as my invention is:

1. In an apparatus of the character described, a target guide, a target throwing member operable to impel a target from the guide, means for adjusting the guide for different trajectories, means operable from a remote point for actuating the first named means, and means for coordinating the operation of adjusting the guide and throwing targets.

2. In an apparatus of the character described, an adjustable target guide, a resilient target throwing member operable to impel a target from the guide, and a single means operable from a remote point for simultaneously stressing the throwing member to effect the operation of the target throwing member and adjusting the guide to produce a different trajectory after each actuation of the target throwing member.

3. In an apparatus of the character described, a target guide, a target throwing member operable to impel a target from the guide, means operable from a point remote from the apparatus for simultaneously effecting the operation of the target throwing member and adjusting the guide to produce a different trajectory after each actuation of the target throwing member, means operable to prevent the simultaneous operation of the target throwing member by the first named means, and means independent of the first named means for operating the target throwing member.

4. In an apparatus of the character described, a supporting frame, a target guide, a target throwing shaft journaled in the frame, an arm carried by said shaft and arranged to sweep the guide, a second shaft, a connection between the second shaft and said guide whereby rotation of said shaft adjusts the guide to produce different trajectories, means for rotating the first named shaft, means for rotating the second shaft, and means for independently operating said shafts.

5. In an apparatus of the character described, a supporting frame, a target guide, a target throwing shaft journaled in the frame, an arm carried by said shaft and arranged to sweep the guide, a second shaft, a connection between the second shaft and said guide whereby rotation of said shaft adjusts the guide to produce different trajectories, means for rotating the first named shaft, means for rotating the second shaft, means for permitting independent operation of said shafts,

and means for coordinating said shafts to operate simultaneously.

6. In an apparatus of the character described, a supporting frame, a target guide, a target throwing shaft journaled in the frame, an arm carried by said shaft and arranged to sweep the guide, a second shaft, a connection between the second shaft and said guide whereby rotation of said shaft 5 adjusts the guide to produce different trajectories, means for rotating the first named shaft, means for rotating the second shaft, a detachable drive connection between said shafts, and a control member positioned at a point remote from the apparatus and arranged to simultaneously operate both of said shafts when said drive connection is operative and to rotate but one of said shafts when said drive connection is inoperative.
7. In an apparatus of the character described, a supporting frame, a target throwing shaft journaled in the frame, an arm carried by said shaft and arranged to sweep the guide, a second shaft, a connection between the second shaft and said guide whereby rotation of said shaft adjusts the guide to produce different trajectories, means for rotating the first named shaft, means for rotating the second shaft, a detachable drive connection between said shafts, a control member positioned at a point remote from the apparatus and arranged to simultaneously operate both of said shafts when the drive connection is operative and to rotate only said first shaft when the drive connection is inoperative, and a second control member remote from the apparatus for operating the second named shaft independent of the first shaft when said drive connection is inoperative.
8. In an apparatus of the character described, a supporting frame, a target throwing shaft journaled in the frame, an arm carried by said shaft and arranged to sweep the guide, a second shaft, a connection between the second shaft and said guide whereby rotation of said shaft adjusts the guide to produce different trajectories, means for rotating the first named shaft, means for rotating the second shaft, a detachable drive connection between said shafts, a control member positioned at a point remote from the apparatus and arranged to simultaneously operate both of said shafts when said drive connection is operative and to rotate only said first named shaft when the drive connection is inoperative, a control rod extended from the first named shaft to a point remote from the apparatus and adapted upon rotation, with the drive connection in operation, to rotate both of said shafts, a second control rod extended from the second shaft to permit independent operation thereof when the

drive connection is inoperative, and means actuated by manipulation of one of said control rods to actuate said drive connection.

9. An apparatus of the character described, including a stationary target guide, means for supplying targets thereto, and means for discharging targets from the guide singularly or in simultaneous groups.

10. An apparatus of the character described, including a target guide, a target feed trough communicating therewith, means for feeding targets to the guide from said trough in pairs, and means operable to prevent the feeding to the guide of one of the targets of any pair.

11. An apparatus of the character described, including a target guide, a target feed trough communicating therewith, means for feeding targets to the guide from said trough in pairs, and means operable to prevent the feeding to the guide of either one of the targets of any pair.

12. An apparatus of the character described, including a target guide, a target feed trough communicating therewith, means for feeding targets to the guide from said trough in pairs, and means operable from a point remote from the apparatus to prevent the feeding to the guide from the trough of one of the targets of any pair.

13. An apparatus of the character described, including a target guide, a trough communicating at one end of said guide for feeding targets thereto, a yieldable stop engaging the innermost target of the trough to position the same for engagement with a target throwing member arranged to sweep the guide, and means cooperating with said stop to prevent the accidental dislodgment of a target upon striking the stop.

14. An apparatus of the character described, including a target guide, a feed trough communicating with the guide for supplying targets thereto in pairs, a partition in said trough separating the targets of each pair, and a stop movable in said trough to hold one target of a pair from being fed to the guide whereby targets may be fed thereto in either doubles or singles.

15. An apparatus of the character described, including a target guide, a feed trough communicating with a guide for supplying targets thereto in pairs, a partition in said trough separating the targets of each pair, and stop fingers movable to project into either side of the trough to engage either one of the targets of a pair whereby but a single target may be fed to the guide.

16. An apparatus of the character described, a strip along which targets are adapted to be accelerated from rest to discharge velocity, and means for changing the form of said strip throughout the major portion of its length to vary the resulting trajectories of targets accelerated thereover.

- 6
17. In an apparatus of the character described, a strip along which targets are adapted to be accelerated from rest to discharge velocity, and means for changing the 5 form of said strip to vary the resulting trajectories.
18. An apparatus of the character described, including a target guide comprising side plates and a bottom race member 10 of yieldable material and made fast at its inner end, means for flexing said race member along the major portion of its length whereby targets impelled from the apparatus may be thrown at various trajectories.
19. An apparatus of the character described, including a target guide comprising side plates and a bottom race member 15 of yieldable material and made fast at its inner end, and means controlling the curve 20 along which said race member is flexed.
20. An apparatus of the character described having a target guide including a race member and along which targets are impelled by a suitable throwing member in 25 pairs and singles, and means associated with the guide whereby the targets of any simultaneously thrown pair will have different 30 trajectories.
21. An apparatus of the character described having a target guide including a race member and through which targets are 35 impelled by a suitable throwing member in pairs and singles, a flexible end portion carried by one longitudinal edge of the race member, and means for adjusting said flexible member portion whereby the targets of any pair impelled from the guide will have 40 different trajectories.
22. In an apparatus of the character described, a throwing member, and a duplex 45 magazine for presenting targets to said member.
23. In an apparatus of the character described, a throwing member, a duplex magazine for presenting targets to the throwing 50 member, and means for controlling the operation of the magazine. 45
24. In an apparatus of the character described, a throwing member, a duplex magazine for presenting targets to the throwing 55 member, and means for controlling the operation of the magazine, said means being positioned at a point remote from the apparatus. 50
25. In an apparatus of the character described, a throwing member, a magazine for presenting targets to the throwing member, and an adjustable, yieldable member 60 permitting the employment of targets of different sizes in the magazine. 55
26. In an apparatus of the character described, a throwing member, a magazine for presenting targets to the throwing member, means for feeding targets from the magazine to the throwing member, and means for 65 adjusting said feed means to accommodate targets of different sizes. 60
27. In an apparatus of the character described, a target supply magazine, means for feeding targets in said magazine to a 70 discharge position, and an adjustable stop against which the inner targets of the magazine are engageable whereby targets of various sizes may be employed in the magazine. 75
28. In an apparatus of the character described, a target supply magazine, means for feeding targets in said magazine to a discharge position, and an adjustable stop 80 against which the inner targets of the magazine are engageable whereby more than one target can be fed at one operation. 80

In testimony whereof I affix my signature.

ERWIN F. BAHLMANN.
